REGENERATOR WITH CHECKERWORK FOR
VERTICAL FLOW OF THE GASEOUS
MEDIA

Carl Otto, Essen, Germany

Application October 5, 1935, Serial No. 43,721
In Germany September 7, 1934

4 Claims. (Cl. 263—19)

It is known to build up the checkerwork of regenerators with square hollow bricks, such bricks having several long square gas ducts formed by cross walls, and longitudinal side walls 5 projecting beyond the cross walls for the purpose of forming a hollow space which connects all gas ducts with each other, the side walls being further provided with ribs running parallel to the cross walls, when the checker brickwork is built 10 up. These ribs fix the distance between adjacent checker bricks and the brickwork confining the heat storage space. In the checker brickwork of long-stretched regenerators, f. i. of the so-called cross regenerators for gas and coke producing chamber ovens continuous horizontal 15 spaces are formed on the full length of the regenerator by the hollows in the cross walls.

The invention has for its aim to divide by the bricks themselves regenerators with vertical flow and built up of such checker bricks into several 20 vertical gas spaces, isolated from each other. For this purpose the horizontal spaces running in the longitudinal direction of the regenerator and formed by the hollows of the cross walls in the checker bricks are interrupted. This is done 25 in the following way: While the longitudinal side walls of most of the checker bricks are extended by rib-like projections so that they project beyond the cross walls, the end cross wall of several 30 bricks is continued over the full length in upward direction of the longitudinal side walls; the bricks are placed one on top of the other in such a way that the continued end cross walls stand one 35 on top of the other forming vertical division walls which extend over the full height of the regenerator, dividing the regenerator into several vertical ducts which are isolated one from the other.

The drawing shows regenerators for a battery of horizontal gas and coke producing chamber 40 ovens and parts thereof. In this drawing—

Fig. 1 is a vertical section in the longitudinal direction of the battery.

Fig. 2a is a longitudinal section in the longitudinal direction of a heating wall through a gas 45 regenerator corresponding to section IIa—IIa of Fig. 1.

Fig. 2b is another section through an air regenerator corresponding to section IIb—IIb of Fig. 1;

Fig. 3a is a vertical central longitudinal section through a top row regenerator brick;

Fig. 3b is an end view;

Fig. 3c is a plan view of the brick shown in Fig. 3a; and

Fig. 3d is a section taken similarly to Fig. 3a,

showing a portion of the brick on a larger scale.

Between the coking chambers a there are the heating walls divided into vertical heating flues b which are connected with air regenerator c and c' and gas regenerator d and d' arranged underneath the heating flues b through ducts e and f. From each pair of twin-flues the up-burning flue is connected with two regenerators for pre-heating gas and air respectively and the down-burning flue is connected with two regenerators 10 for receiving the waste heat. When the regenerator group c, d is working for heating gas and air respectively, the two adjacent regenerator groups c' and d' are supplied with waste heat and as shown vice versa.

The regenerators are filled with checker work as shown in Figs. 1 and 2. One of the checker bricks used in the top layer or row of regenerator checker bricks is shown in Figs. 3a to 3d. The side walls n of each brick form with the cross 20 walls h vertical gas ducts of rectangular section. On the bottom of the brick, the side walls n vertically project over the cross walls h (Fig. 3b); whereby between two layers or superposed rows of checker bricks, horizontal hollow spaces 25 in the longitudinal direction of the regenerator are formed (Figs. 2a and 2b). In order to subdivide these hollow spaces, the one outer cross wall k of some of the bricks has the same height 30 as the side walls n. The walls k of the bricks in the top row project upwardly over the longitudinal side walls (Figs. 3a and 3b) and reach to the top of the regenerator spaces (Figs. 2a and 2b) in order to form separate regenerator sections and completely isolate the vertical 35 gas ducts of each section from those of another section.

As shown in Figs. 2a and 2b cross walls k are provided on some of the bricks in such number that a separate regenerator section always corresponds to an individual heating flue. While a gas regenerator is supplying heat to each second heating flue alternately in one or the other of two adjacent heating walls, an air regenerator is only 40 connected with every second heating flue of one heating wall. The sections into which the regenerators are subdivided by means of the cross walls k therefore have in the air regenerators c and c' double the length of those in the gas regenerators d and d'.

There is known a procedure of removing regenerator checker bricks by means of a carrying plate provided with a wedge at its front part which is pushed under the cross walls of the 55

checker bricks, thus raising the bricks and taking them along when the plate is withdrawn.

In order to follow the same procedure in removing the bricks provided in accordance with 5 the present invention, those bricks having the cross walls k should be placed in the regenerator in such a way that each cross wall k is at the end of the brick remote from the open end of the regenerator.

10 However, the bricks may be arranged in the reverse way, so that the cross walls k are at the ends of the bricks which face the open end of the regenerator. In such case for the removal of 15 said bricks by the carrying plate procedure, spaces

15 m are provided in the walls k , as shown in Figs. 3a and 3d, each such space including a portion leading into the wall k from the outer side of the latter, and including a portion extending laterally away from the first mentioned portion.

20 What I claim is:—

1. A regenerator comprising a chamber and checker bricks therein arranged end to end in each of a plurality of superposed rows, each of 25 said checker bricks being formed with vertical side walls and with vertical cross walls extending between the side walls and spaced apart to form side by side open ended vertical flow passages, certain of said bricks each having all of its cross walls spaced upwardly from the plane 30 of its lower edges of its side walls, and other bricks each having all but one of its cross walls spaced upwardly from the plane of the lower edges of its side walls and having the lower edge 35 of said one cross wall enlarged to extend between the planes of the upper and lower edges

of said side walls, each such enlarged cross wall being in superposed relation with similarly enlarged cross walls of bricks in the different superposed rows, and thereby forming part of a vertical division wall between adjacent end to 5 end sections of the regenerator.

2. A regenerator as specified in claim 1, in which the side walls of the bricks in the top row of checker bricks are below the top of the regenerator chamber, thereby providing a gas space at 10 the top of said chamber, and in which each top row brick having a cross wall enlarged as specified in claim 1, has said cross wall extended upwardly across said gas space, dividing the latter into end to end sections. 15

3. A regenerator as specified in claim 1, which is adapted for the insertion of checker bricks into, and their removal from the regenerator chamber at one end of the latter, and in which the said enlarged cross wall of each brick having such a wall, is at the end of said brick remote from the said one end of said chamber. 20

4. A regenerator as specified in claim 1, which is adapted for the insertion of checker bricks into, and their removal from the regenerator 25 chamber at one end of the latter, and in which the said enlarged cross wall of each brick having such a wall, is at the end of the brick adjacent the said one end of said chamber, and is formed with a recess comprising a portion extending 30 into said cross wall from its outer side, and a portion extending laterally away from the first mentioned portion.
